(57) **CLAIM**

The ornamental design for a polymer composite pulley, as shown and described.

DESCRIPTION

FIG. 1 is a side and top perspective view of a polymer composite pulley showing our new design;
FIG. 2 is a front elevation view thereof.

FIG. 3 is a side and top perspective view of a polymer composite pulley showing an alternative embodiment of our new design;

FIG. 4 is a front elevation view thereof.

FIG. 5 is a side and top perspective view of a polymer composite pulley showing an alternative embodiment of our new design;

FIG. 6 is a front elevation view thereof;

FIG. 7 is a side elevation view thereof.

FIG. 8 is a side and top perspective view of a polymer composite pulley showing an alternative embodiment of our new design; and,

FIG. 9 is a front elevation view thereof.

The broken line representation of environmental structure is for illustrative purposes only and forms no part of the claim.
The boundary lines represent the boundary of the claim.
